2 Sheets-Sheet 2

UNITED STATES PATENT OFFICE

JOHN M. VARBLE AND RICHARD A. SHANNON, OF CANTON, OHIO; SAID SHANNON AS SIGNOR TO SAID VARBLE

CAR RETARDER

Application filed August 26, 1930. Serial No. 477,946.

This invention relates to car retarders, that is a device for handling and classifying railway cars.

A still further object of the invention is to provide a car retarder for handling cars and more particularly for controlling and classifying freight cars.

A still further object of the invention is to provide a device of the above mentioned 10 character especially adapted for use in connection with an electrical apparatus and lighting system also used for this purpose and embodying the subject matter of Patent No. 1,360,150, granted to Richard A. Cannon 15 under date of November 23, 1920.

Other objects and advantages of the invention will become apparent during a study of the following description, taken in connection with the accompanying drawings, 20 wherein:

Figure 1 is a top plan view of the improved car retarder, the cover plate being removed.

Figure 2 is a sectional view taken substantially on the line 2—2 of Figure 1, the cover 25 plate being shown in position.

Figure 3 is a similar view taken substantially on the line 3—3 of Figure 1.

Figure 4 is a perspective view of a braking or retarding bar.

With reference more in detail to the drawings, it will be seen that 5 designates a base. The base 5 is provided with suitable integral supports 6 for supporting a portion of the rails R of a track designated generally by the 35 reference character T and shown to advantage in Figure 1.

In order to grip the wheels of a car and apply pressure which will retard movement of the car along the track there has been provided 40 brake bars 7 and 8 upon opposite sides of each rail. These bars are in the form of steel bars, which are substantially S-shape in cross section as suggested in the drawings and extend longitudinally of the rails, and have, their upper inwardly directed flanges 9 extending above the ball of the rail whereby the flanges 9 of the bars may contact the wheels of the railway car.

The bars 7 and 8 are adapted for movement toward and away from the rails and are

supported on suitable guides 11 and 12 provided on opposite sides of each rail and supported on the upper end of transverse ribs 13 that extend transversely of the base 5 and in suitable spaced relation as will be manifest. The lower or base flanges 10 of the brake bars rest on the guides 11 and 12.

As before intimated these brake bars are to be mounted for movement toward and away from the rails and therefore the outer bars 7 are provided with bell cranks 13' and 14 secured to the flanges 10 of the bars by a suitable bolt 15 and to an operating rod 16 that extends transversely across the rails. Each of the bars 8 has its flange 10 pivoted to one corner of pivotally mounted substantially triangular shaped plates 17 and 18, which plates 17 and 18 are in turn pivotally connected at one corner to an operating rod 19 that also extends transversely of the track.

One end of the operating rod 16 is pivotally connected to a pivotally mounted substantially triangular plate 20 disposed at one side of the base 5, and a corresponding end of the operating rod 19 is pivotally connected 75 to a substantially triangular plate 21, likewise mounted on the same side of the base 5 as the plate 20. A horizontally disposed arm 22 extends between the operating rods 16 and 19 and parallel with said rods. To 80 the outer end of the arm 22 is rockably mounted a substantially V-shaped plate 23 that at one end thereof has a resilient connection 24 with the free corner of the plate 20. The plate 23 intermediate its ends has also a connection 25 similar to the connection 24 with one corner of the plate 21. A suitable spring 26 is anchored at a fixed point adjacent the side edge of base 5 and has its other end operatively connected to the arm 22.

Also mounted to one side of the base 5 is a suitable pressure cylinder 27 that is suitably operated by means not shown, from a point remote with respect to the track and cylinder 27 has the piston thereof provided with a suitable rod 28, the outer end of which has a link connection 29 with the plate 23.

It will be readily seen that the operating rods 16 and 19 will be moved in a corresponding direction and moving the brake bars 7

and 8 toward the rails R and into engagement with the wheels of the car. The car wheels will therefore be engaged by flanges 10 of the bars 7 and 8 and rotation of the 5 wheels and movement of the car along the tracks will be retarded.

The gripping action will of course be controlled by the amount of pressure in the cylinder and therefore it is apparent that the car 10 may be gradually forced to a stop or quickly brought to a stop as may be desired, and dependent of course upon the pressure in the cylinder 27.

In order to assure a uniform gripping action of the bars 7 and 8 throughout their 15 entire length, there are provided adjacent each of the bars, and on opposite sides of the rails R a plurality of springs 30. Each of the springs 30 is disposed at substantially a 20 forty five degree angle relative to the support 6 and its braking bar, and each of the springs at one end bear against an obliquely disposed lug 31 rising from the base 5, and at its opposite end each of the springs 30 is provided 25 with an apertured lug 32 whereby the same may be connected to the flange 10 of a braking bar through the medium of a suitable fastening bolt 33. Suitable spacer sleeves 34 are disposed about the bolts between the lugs 32 30 and flanges 10.

The springs 30 being disposed at an approximately forty five degree angle relative to the support 6, the possibility of the spring breaking is reduced to a minimum.

35 Supported in a suitable manner on the base 5 and providing a protective covering for the spring and other movable parts of the apparatus associated with the base, is a metallic cover plate 35 of suitable construction and 40 provided with suitable longitudinally extending slots 36 for accommodating the braking bars 7 and 8.

As before stated, this particular type of 45 car retarder for use in terminal yards is especially adapted to be used in conjunction with a lighting system forming the subject matter of the patent identified hereinbefore and it will be further seen, that a retarding device of this character provides a strong, 50 durable, and efficient device for bringing freight cars to a stop and in controlling from a remote point the freight cars when it is desired to classify the latter.

Even though we have herein shown and 55 described the preferred embodiment of our invention, it is to be understood that the same is susceptible to changes fully comprehended by the spirit of the invention as herein described, and the scope of the appended claims.

60 Having thus described our invention, what we claim as new is:

1. In a car retarding apparatus, and in combination, a base, a rail support integral with said base, a rail on said support, guides 65 on said base at opposite sides of said support,

and at right angles thereto, wheel engaging bars disposed transversely of said guides parallel to said rail on opposite sides of said rail, each of said wheel engaging bars provided on its upper edge with an inwardly directed flange adapted to overlie and parallel the ball of said rail, and means for moving said wheel engaging bars toward and away from said rail. 70

2. A railway car retarder comprising in combination a base having a recess in the top thereof, spaced parallel longitudinal rail supports arranged in the recess, brake bar guides in the recess at opposite sides of each of said rail supports, and a cover plate for said recess having slots accommodating the rails and brake bars. 75

80 3. A railway car retarder comprising in combination a base having spaced parallel longitudinal supports for the rails, and transverse supports for brake bars on opposite sides of the rails, and a cover plate having spaced parallel depending flanges resting on the base and transverse supports respectively, said plate in the top thereof 85 being provided with longitudinal slots accommodating the rails and brake bars. 90

95 4. A railway car retarder comprising in combination, shiftable brake bars on opposite sides of each of the rails of the railway, a base provided with a recess, angularly disposed supports in the recess for the rails and brake bars respectively, a cover plate for the recess provided with depending flanges for rest on certain of said supports and said base 100 respectively whereby to support the cover plate in spaced relation to the top of said base, and said cover plate provided with slots adjacent the rails for accommodating the 105 brake bars.

In testimony whereof we affix our signatures.

JOHN M. VARBLE.
RICHARD A. SHANNON.
